SAW SET

Edgar Platter, Albuquerque, N. Mex.

Application March 30, 1945, Serial No. 585,595

3 Claims. (Cl. 76—72)

1

The present invention relates to new and useful improvements in saw sets of a type as covered in my prior U. S. Letters Patent No. 2,416,695, dated December 27, 1938.

An important object of the present invention is to provide a saw set of the aforementioned character in which a tooth-setting jaw is provided having an elongated head adapted to contact the beveled side of the tooth for exerting pressure thereon during the saw setting action, the head of the saw setting jaw being adapted for use with fine or coarse saw teeth and embodying means for adjusting the head of the setting jaw in accordance with the character of the tooth being set.

A further object of the present invention is to provide a spring-actuated wedge adapted to grip the side of the saw for holding the same firmly while the teeth are being set.

A further object of the invention is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a side elevational view of the saw set with parts shown in section and illustrating the tooth-setting head in use.

Figure 2 is an edge elevational view thereof.

Figure 3 is a vertical sectional view taken substantially on a line 3—3 of Figure 1.

Figure 4 is a transverse sectional view taken substantially on a line 4—4 of Figure 1.

Figure 5 is a vertical sectional view taken substantially on a line 5—5 of Figure 1, and illustrating the anvil-carrying section.

Referring now to the drawing in detail, wherein for the purpose of illustration I have disclosed a preferred embodiment of the invention, the numeral 1 designates the jaw-carrying section, while the numeral 2 designates the anvil-carrying section.

The section 1 is relatively longer than the section 2, the section 1 tapering toward its upper end, as indicated at 3, and terminates in a flat surface to provide a striking head 4 to receive a hammer blow by a suitable tool.

The section 1 is provided with a shoulder 5 at the junction of the tapered portion thereof with

2

the section 2 and the section 2 has a flat upper end disposed in abutting relation with the shoulder 5, as well as a flat inner face 6 for disposal in face-to-face contact with the flat inner face 7 of the section 1.

The sections 1 and 2 are detachably secured to each other by a bolt 8 which extends through the section 1 and is threaded in the section 2.

The lower portions of each of the sections are 10 reduced and provided with flat confronting faces disposed in spaced-apart relation with respect to each other for receiving a saw blade 9 between the same and the opposed face of the section 1 has a recess 10 formed therein and in which is 15 slidably mounted a wedge block 11 yieldably urged downwardly toward the lower end of the section 1 by a coil spring 12 to set up frictional wedging action against the saw blade.

The inner portion of the spaced confronting 20 faces of the sections are formed with registering recesses 13 and 14, respectively, the recess 13 having a setting jaw 15 mounted therein of elongated construction and formed with beveled upper and lower edges 16 and 17, the beveling 16 being relatively wider than the beveling 17, as will be apparent from an inspection of Figure 1 of the drawing.

The jaw 15 is formed on a square shank 18 30 slidably mounted in a complementary shaped passage 19 in the section 1 and projecting from the shank 18 is a screw 20 on which a nut 21 is threaded and retained in a chamber 22 in the section 1 with the edges of the nut projecting outwardly at opposite sides of the section 1, as indicated in Figure 2 of the drawing, to provide finger-gripping means for the nut to adjust the head 15 into and out of contacting engagement with one side of the teeth 23 of the saw 9.

Positioned in the recess 14 is an anvil 24 like- 40 wise of elongated construction formed on its square-shaped shank 25 from which a screw 26 projects for manipulation by a nut 27 carried in the section 2 similar to the nut 21 of the section 1 and adapted upon manipulation of the nut 27 to move the anvil toward and away from the head 15.

As illustrated in Figure 3 of the drawing, one side of the wedge 11 is provided with a laterally extending pin 28 projecting outwardly of the section 1 through an opening 29 for releasing the wedge from the saw, when desired.

In the operation of the device, the saw blade 9 is positioned between the spaced-apart confronting faces of the lower ends of the sections 1 and 2 and the wedge 11 is moved downwardly

by the pin 28 to cause friction gripping engagement thereof with the saw.

The teeth 23 of the saw are disposed between the head 15 and handle 24 so that upon striking a hammer blow upon the striking head 4, the beveled edge of the setting jaw 15 will bend the teeth of the saw against the anvil at the desired angle.

Either of the beveled edges 16 or 17 may be brought into contacting engagement with the teeth of the saw in accordance with the size of the teeth being set.

It is thought from the foregoing description that the advantages and manner of operation of the device will be readily apparent to those skilled in the art.

It is to be understood that changes may be made in the construction and in the arrangement of the several parts as herein described and illustrated in the accompanying drawing, provided that such changes fall within the scope of the appended claims.

Having thus described the invention, what I claim is:

1. A saw set comprising a body having spaced inner faces to receive a saw blade between the same, and a saw tooth-receiving chamber at the inner ends of the faces, a tooth-engaging jaw positioned at one side of said chamber, said jaw being of elongated construction with its opposite ends beveled for selective engagement with the tooth of the saw, an anvil positioned in the chamber at the opposite side of the tooth, independent means for adjusting the jaw and the anvil relative to each other, said body having a striking head adapted for receiving a hammer blow at one end thereof, a wedge slidably mounted in

5 the body, spring means engaging the wedge to urge the latter into friction gripping engagement with the saw, said body having an opening therein adjacent the wedge, and a pin carried by the wedge and projecting outwardly of the body through said opening and providing finger gripping means for releasing the wedge for engagement with the saw.

10 2. In a saw set, a body comprising spaced inner faces to receive a saw blade therebetween and a saw tooth receiving chamber at the inner ends of said faces, a tooth engaging jaw embodying an elongated head mounted for lateral movement within said chamber, an anvil mounted for lateral movement within said chamber and cooperating with said jaw, means for adjustably moving said jaw toward and from said anvil, and means for adjustably moving said anvil toward and from said jaw.

15 3. In a saw set, a body comprising spaced inner faces to receive a saw blade therebetween and a saw tooth receiving chamber at the inner ends of the faces, a tooth engaging jaw embodying an elongated head mounted for lateral movement within said chamber, an anvil mounted for lateral movement within said chamber and cooperating with said jaw, means for adjustably moving said jaw toward and from said anvil, means for adjustably moving said anvil toward and from said jaw, one of said faces being provided with an elongated recess adjacent its lower end thereof, and a wedge yieldably and slidably mounted within said recess adapted for frictional gripping engagement with the saw when positioned within said faces to secure the latter against movement.

EDGAR PLATTER.
